UNITED STATES PATENT OFFICE.

LONNIE ADKISSON, OF LOUISVILLE, KENTUCKY.

LOCOMOTIVE THROTTLE ATTACHMENT.

Application filed October 6, 1927. Serial No. 224,405.

The present invention relates to an attachment for the throttle of a railroad locomotive and has for its prime object to provide a structure which when properly adjusted, prevents the engineer from completely shutting off the throttle in one stroke, but forces the engineer to move the throttle to an idling position first and then perform a certain releasing operation which will allow him to completely close the throttle.

Very frequently, an engineer is forced to bring his locomotive and train to a sudden stop and in certain instances, the engineer naturally becomes excited and shuts the throttle completely off with one throw which immediately admits air into the cylinder to replace the superheated steam and this sudden cooling causes considerable damage as is well recognized in this art. I realize that other attempts have been made to solve this problem, examples of which will be found in Letters Patent Nos. 1,427,969 and 1,564,465. It is an important object of my invention to improve upon the structures shown in these patents to provide a device which is simpler in its construction, truly in the nature of an attachment in its capability of operative association with mechanisms now in common use and inexpensive to install.

A still further important object of the invention resides in the provision of an attachment of this nature which is thoroughly efficient and reliable in its operation, easy to manipulate, strong and durable, not likely to easily become out of order, adjustable to an operative or inoperative relationship with the throttle and otherwise well adapted to the purpose for which it is designed.

With the above and numerous other objects in view as will appear as the description proceeds, the invention resides in certain novel features of construction, and in the combination and arrangement of parts as will be hereinafter more fully described and claimed.

In the drawing:—

Figure 1 is a top plan view of a throttle control with my attachment associated therewith,

Figure 2 is a perspective view of those portions of the attachment mounted on the boiler,

Figure 3 is a sectional side elevation thereof,

Figure 4 is an enlarged detail sectional view taken transversely therethrough, substantially on the line 4—4 of Figure 3,

Figure 5 is another transverse section therethrough taken substantially on the line 5—5 of Figure 2,

Figure 6 is a fragmentary perspective view of the throttle controller with portions of my attachment associated therewith,

Figure 7 is a perspective view of the adjusting member, and,

Figure 8 is a fragmentary perspective view of the sliding bolt.

Referring to the drawings in detail, it will be seen that the numeral 5 denotes a bracket arm attached to the cabin end of the boiler 6 in the usual well known manner. The controller is pivotally engaged at one end to the end of the bracket arm 5 as is indicated at 8 and has the usual engagement intermediate its ends with the throttle rod 9. The numeral 10 denotes the usual rack engageable by the sliding dog 11 on the controller 7, this sliding dog 11 having a shank 12 with a link connection to a hand lever 13, the link being indicated specifically by the numeral 14. All the parts thus far described are of well known construction and now in actual use upon locomotives throughout the country. When it is desired to throw the controller 7 it is necessary to grip the hand lever 13 to pull upon the link 14 so as to slide the dog member 11 away from the rack 10. The upper position of the controller 7 is Figure 1, that is, when its free end is close to the boiler is the off position and the free end is moved away from the boiler to turn on the steam, that is, open the throttle valve.

As soon as the hand lever 13 is released, a spring, not shown, returns the dog member 11 into engagement with the rack 10 as will be apparent to those skilled in this art.

Referring now to the details of my attachment, it will be seen that the letter B

denotes generally a bracket comprising a plate 16 which is secured to the end of the boiler in the cabin by any suitable fastening means. An arm 17 projects outwardly or laterally from the plate 16 and has a longitudinally extending slot 18 formed therein. An inclined brace arm 19 is connected with the outer end of the arm 17 and with the lower portion of the plate 16. The arm 17 is formed in its upper surface with a longitudinally extending channel or recess 20. A shank 21 is slidably in the recess 20 and a bolt 22 is threadedly engaged therewith and extends through the slot 18 so that the shank 21 may be locked onto the arm 17 in different adjusted extended position. The outer end of this shank merges into an enlarged head portion 23 which is formed with a transversely extending bore 24 that slidably receives a bolt 25 having an upstanding shoulder 26 projecting through an opening 27 in the top of the head which communicates with the bore 24. A plate 28 is fixed on one side of the head 23 to extend partially over one open end of the bore 24 and has an opening for slidably receiving a rod 29, the outer end of which has threadedly engaged thereon a stop nut 30. The other end of the rod 28 is threadedly engaged in an opening 31 provided in the upstanding lug 26. A spring 32 of the coil type is disposed about the rod 29 and impinges against the lug 26 and the plate 28 so as to normally hold the rounded nose-like end 25' of the bolt 25 extended as is illustrated in Figure 5 so that the lug 26 abuts one end of the opening 27. A latch 34 is pivoted as at 35 on top of the head 23 adjacent the shank 21 and extends outwardly from the shank to provide an inclined edge 36 and a stop shoulder 37 and a finger 38 which is engageable by the lug 26. A stem 39 is rotatable in an opening in the head 23 and has an eccentric pin 40 at its upper end and a wing-like knob 41 on its other end, said other end is formed with a transverse opening 42 to receive a cotter pin 43 that extends through a depending lug 44 on the head 23 so that this stem with its eccentric pin 40 may be held in different adjusted positions. When in one position the pin holds the spring 32 compressed and the latch 34 out of the way and also the nose 25' out of the way, but in its other position, the pin merely limits the movement of the latch 34 in one direction is will be quite apparent. The controller 7 has a finger 45 of an inverted L-shaped formation bolted or otherwise fastened thereto as is indicated at 46. A horizontal L-shaped finger 47 is fixed in any preferred manner as at 48 to the shank 12 of the dog member 11. The parts are so disposed that when the eccentric pin 40 is in its released position, that is, allows the latch 34 to swing so that the lug 26 may abut the end of the opening 27 as shown in Figure 5, and the controller 7 is pushed inwardly to shut off the steam, the finger 45 will engage the rounded nose 25' and force the bolt 25 inwardly and this will leave the latch 34 in the same position so that as the lever is pushed a little further, the finger 45 will abut against the shoulder 37 so that the throttle 7 cannot be pushed all the way in to completely close the throttle valve, but the operator must release his grip on the hand lever 13 so as to engage the dog device 11 with the rack 10 and simultaneously with this action the finger 47, in Fig. 1, moves to the left and abuts the latch 34 so as to swing said latch, in Fig. 1, in a clockwise direction, out of the path of movement of the finger 45. Thus the operator may then actuate the lever 13 to again release the dog member 11 and push the controller 7 all the way forward to a completely closed position.

In opening the throttle the controller 7 is moved outwardly from the boiler and the finger 45 will engage the inclined edge 36 so as to swing the latch, in Fig. 1, in a clockwise direction so as to push the bolt to the left of this finger and compress the spring 32 so that as soon as the controller has been pushed out farther, this spring 32 will again extend the nose 25' outwardly and cause the lug 26 to abut the end of the opening 27 thereby swinging the latch 34 in a counter-clockwise direction and leaving its shoulder 37 in the path of movement of the finger 45. Thus the throttle cannot be completely closed in one actuation. This is very important in the super-heated steam locomotives now in use because when an engineer suddenly locates an obstacle or obstruction on the track, he naturally becomes somewhat excited and tends to throw off the throttle as quickly as possible, and if the throttle is completely thrown off, great damage will be done to the cylinder. With this device, however, the engineer is only able to throw the throttle in an idling position and then must hesitate momentarily before completely closing the throttle and this has been found sufficient to prevent any excessive damage.

It is thought that the construction, operation, utility, and advantages of this invention will now be quite apparent to those skilled in this art without a more detailed description. It will be seen that at times this attachment will not be desirable as in shifting about the roundhouse, and in the yards, and therefore I have provided the structure for actuating the pin 40 so that the latch 34 and associated parts may be pushed out of the way to an inactive position.

The present embodiment of the invention however, has been disclosed in detail merely by way of example since in actual practice it attains the features of advantage enumer-

ated as desirable in the statement of the invention and the above description. It will be apparent that changes in the details of construction, and in the combination and arrangement of parts may be resorted to without departing from the spirit or scope of the invention as hereinafter claimed or sacrificing any of its advantages.

Having thus described my invention, what I claim as new is:—

1. An attachment of the class described for the throttle controlling mechanism wherein the mechanism includes a dog structure of a locomotive; comprising a head, a latch pivotally mounted on the head, a bolt 75
15 slidable in the head and having one end projectable therefrom, a lug projecting laterally from the bolt to engage the latch, spring means operatively connected with the bolt for normally holding said one end extended and said lug in a position to place the latch in a predetermined position, a stop finger on the controller of the mechanism for engaging the extended end of the bolt 20
25 to move the same inwardly, and a releasing finger on the dog structure of the controller and movable therewith to actuate the latch in an out of the way position from the first finger.
2. An attachment of the class described for the throttle controlling mechanism wherein the mechanism includes a dog structure of a locomotive; comprising a head, a latch pivotally mounted on the head, a bolt 30
35 slidable in the head and having one end projectable therefrom, a lug projecting laterally from the bolt to engage the latch, spring means operatively connected with the bolt for normally holding said one end extended and said lug in a position to place the latch in a predetermined position, a stop finger on the controller of the mechanism for engaging the extended end of the bolt to move the same inwardly, and a releasing finger 40
45 on the dog structure of the controller and movable therewith to actuate the latch in an out of the way position from the first finger, said latch having a stop shoulder for engagement by the stop finger and an inclined edge engageable by the stop finger.
3. An attachment of the class described for the throttle controlling mechanism wherein the mechanism includes a dog structure of a locomotive; comprising a head, a latch pivotally mounted on the head, a bolt 50
55 slidable in the head and having one end projectable therefrom, a lug projecting laterally from the bolt to engage the latch, spring means operatively connected with the bolt for normally holding said one end extended and said lug in a position to place the latch in a predetermined position, a stop finger on the controller of the mechanism for engaging the extended end of the bolt to move the same inwardly, and a releasing finger 60
65 on the cabin end of a boiler.
4. In combination with the throttle control mechanism of a steam locomotive; wherein said mechanism comprises a pivotally mounted controller, a rack, a slideable dog member on the controller, a link engaged therewith, and a hand lever pivoted on the controller and engaged with the link so that the dog may be engaged and released in respect to the rack; of an attachment comprising a head, a bolt slidable transversely 75
80 through the head, a latch pivoted on the head, a lug projecting from the bolt to engage the free end of the latch, spring means associated with the bolt to normally hold one end thereof extended and the lug in engagement with the free end of the latch and the latch in a predetermined position, a finger fixed to the controller and abuttable with the extended end of the bolt to push the bolt inwardly and with the latch to be 85
90 stopped by the latch, and a second finger fixed to the link and movable therewith so that the hand lever may be actuated to cause this second finger to engage the latch when the bolt is retracted to push the latch 95
100 out of the way of the first finger.
5. In combination with the throttle control mechanism of a steam locomotive; wherein said mechanism comprises a pivotally mounted controller, a rack, a slideable dog member on the controller, a link engaged therewith, and a hand lever pivoted on the controller and engaged with the link so that the dog may be engaged and released in respect to the rack; of an attachment 105
110 comprising a head, a bolt slidable transversely through the head, a latch pivoted on the head, a lug projecting from the bolt to engage the free end of the latch, spring means associated with the bolt to normally hold one end thereof extended and the lug in engagement with the free end of the latch and the latch in a predetermined position, a finger fixed to the controller and abuttable with the extended end of the bolt to push the bolt inwardly and with the latch to be 115
120 stopped by the latch, and a second finger fixed to the link and movable therewith so that the hand lever may be actuated to cause this second finger to engage the latch when the bolt is retracted to push the latch out of the way of the first finger, and means for adjustably mounting the head on the cabin end of a boiler.
6. In combination with the throttle con- 125
130

trol mechanism of a steam locomotive; wherein said mechanism comprises a pivotally mounted controller, a rack, a slidable dog member on the controller, a link engaged therewith, and a hand lever pivoted on the controller and engaged with the link so that the dog may be engaged and released in respect to the rack; of an attachment comprising a head, a bolt slidable 10 transversely through the head, a latch pivoted on the head, a lug projecting from the bolt to engage the free end of the latch, spring means associated with the bolt to normally hold one end thereof extended and the lug in engagement with the free end of the latch and the latch in a predetermined position, a finger fixed to the controller and abuttable with the extended end of the bolt to push the bolt inwardly and with the latch 15 to be stopped by the latch, and a second finger fixed to the link and movable therewith so that the hand lever may be actuated to cause this second finger to engage the latch when the bolt is retracted to push the latch out of the way of the first finger, a shank extending from the head, a bracket for attachment to the cabin head of a boiler, an arm projecting from the bracket and having a recess to slidably receive the shank, 20 means for holding the shank in different adjusted extended positions in respect to said arm.

7. In combination with the throttle control mechanism of a steam locomotive; wherein said mechanism comprises a pivotally mounted controller, a rack, a slidable dog member on the controller, a link engaged therewith, and a hand lever pivoted on the controller and engaged with the link so that the dog may be engaged and released in respect to the rack; of an attachment comprising a head, a bolt slidable transversely through the head, a latch pivoted on the head, a lug projecting from the bolt to engage the free end of the latch, spring means associated with the bolt to normally hold one end thereof extended and the lug in engagement with the free end of the latch and the latch in a predetermined position, a finger fixed to the controller and abuttable with the extended end of the bolt to push the bolt inwardly and with the latch to be stopped by the latch, and a second finger fixed to the link and movable therewith so that the hand lever may be actuated to cause this second finger to engage the latch when the bolt is retracted to push the latch out of the way of the first finger, a shank extending from the head, a bracket for attachment to the cabin head of a boiler, an arm projecting from the bracket and having a recess to slidably receive the shank, said arm having a slot extending longitudinally of its recess, and a bolt threadedly engaged in the shank 25 and extending through the slot so that it

may be tightened to hold the shank in different adjusted extended position.

8. In combination with the throttle control mechanism of a steam locomotive; wherein said mechanism comprises a pivotally mounted controller, a rack, a slidable dog member on the controller, a link engaged therewith, and a hand lever pivoted on the controller and engaged with the link so that the dog may be engaged and released in respect to the rack; of an attachment comprising a head, a bolt slidable transversely through the head, a latch pivoted on the head, a lug projecting from the bolt to engage the free end of the latch, spring means associated with the bolt to normally hold one end thereof extended and the lug in engagement with the free end of the latch and the latch in a predetermined position, a finger fixed to the controller and abuttable with the extended end of the bolt to push the bolt inwardly and with the latch to be stopped by the latch, and a second finger fixed to the link and movable therewith so that the hand lever may be actuated to cause this second finger to engage the latch when the bolt is retracted to push the latch out of the way of the first finger, said latch having a stop shoulder engageable by the first finger and an inclined edge engageable by the first finger, said stop shoulder preventing the complete inward throw of the controller and the inclined edge causing the movement of the latch to an out of the way position as the controller is initially moved to its on position.

9. In combination with the throttle control mechanism of a steam locomotive; wherein said mechanism comprises a pivotally mounted controller, a rack, a slidable dog member on the controller, a link engaged therewith, and a hand lever pivoted on the controller and engaged with the link so that the dog may be engaged and released in respect to the rack; of an attachment comprising a head, a bolt slidable transversely through the head, a latch pivoted on the head, a lug projecting from the bolt to engage the free end of the latch, spring means associated with the bolt to normally hold one end thereof extended and the lug in engagement with the free end of the latch and the latch in a predetermined position, a finger fixed to the controller and abuttable with the extended end of the bolt to push the bolt inwardly and with the latch to be stopped by the latch, and a second finger fixed to the link and movable therewith so that the hand lever may be actuated to cause this second finger to engage the latch when the bolt is retracted to push the latch out of the way of the first finger, a stem rotatable in the head, an eccentric pin mounted on the stem and abuttable by the latch, so that the stem may be adjusted to place the pin in different 130

positions, one of which limits the movement of the latch when active and the other moves the latch to an inactive position and the bolt through the lug to a retracted position.

5 In testimony whereof I affix my signature.
